United States Patent Office

Des. 187,325
Patented Mar. 1, 1960

187,325

DRESS OR THE LIKE

Ceil Chapman, New York, N.Y., assignor to Samuel Chapman, Inc., New York, N.Y.

Application November 18, 1959, Serial No. 58,391

Term of patent 3½ years

(Cl. D3—26)

Fig. 1 is a front view of a dress or the like, showing my new design.

Fig. 2 is a rear view thereof.

I claim:

The ornamental design for a dress or the like, substantially as shown.
